MULTIPLE TEMPERATURE REFRIGERATOR

Edmund F. Schweller, Dayton, Ohio, assignor to
General Motors Corporation, Dayton, Ohio, a
corporation of Delaware

Application March 19, 1945, Serial No. 583,620

4 Claims. (Cl. 62—116)

1

This invention relates to refrigeration and particularly to a refrigerator cabinet having compartments maintained at different temperatures relative to one another.

It is an increasing problem in household refrigerator cabinet construction to provide for the freezing of certain substances while at the same time providing separate and different temperatured compartments for the storage of various food products. Present day refrigeration demands in the ordinary household, include along with a compartment for freezing water or desserts, etc., for table use and a compartment where cooked food products and raw vegetables and the like may be stored without undue drying, ample space or a fairly large compartment for the storage of pre-frozen meats, berries, vegetables, etc. It is a refrigerator manufacturer's problem to meet these demands without materially increasing the size of a refrigerator cabinet and to economically refrigerate such compartments to different temperatures relative to one another.

An object of my invention is to provide an improved refrigerating apparatus of the household refrigerator type wherein the evaporator of a primary refrigerating system cools one compartment to a predetermined low temperature and is utilized for rendering a plurality of other closed refrigerant circuits effective to cool other compartments of the refrigerator to different temperatures relative to one another.

Another object of my invention is to provide an improved household refrigerator having superimposed food storage compartments the intermediate compartment of which is cooled by an evaporator of a primary refrigerating system and the compartments above and below the intermediate compartment cooled by closed secondary refrigerant circuits rendered effective by the primary evaporator and one of which circuits has capillary means therein for lifting liquid refrigerant upwardly.

A further and more specific object of my invention is to provide a household refrigerator with a plurality of separate compartments all insulated from one another and to arrange a refrigerating system and closed refrigerating circuits within the refrigerator in such a manner as to refrigerate the compartments to different temperatures relative to one another whereby freezing of substances may take place in one compartment, a temperature maintained within another compartment for holding pre-frozen foods and a higher temperatured compartment of

2

higher relative humidity for the storage of certain other food products.

Further objects and advantages of the present invention will be apparent from the following description, reference being had to the accompanying drawings, wherein one form of the present invention is clearly shown.

In the drawings:

Fig. 1 is a front view of a refrigerator cabinet having my invention embodied therein; and Fig. 2 is an enlarged side view partly in elevation and partly in vertical section of the refrigerator cabinet disclosed in Fig. 1.

Referring to the drawings, for illustrating my invention, I have shown in Fig. 1 thereof a refrigerating apparatus of the household type. This apparatus comprises a cabinet 10 enclosed in metal walls 11 and provided with three superimposed or vertically aligned food storage compartments 12, 13 and 14, formed by metal liners 15, 16 and 17 (see Fig. 2), and being normally closed by doors 18, 19 and 20 respectively and a lower machine compartment 21 closed by a door 22. Any suitable insulated material 24 may surround the metal liners beneath the metal walls 11 for insulating the compartments from one another. It is to be understood that a single door may be provided for simultaneously closing all three of the food storage compartments if desired instead of employing the separate doors. In the present structure it is intended that the compartment 12 be utilized for the storage of pre-frozen food products such as meats, berries, vegetables, etc., compartment 13 for freezing desserts for table use or water into ice blocks or cubes, within suitable trays indicated at 25, and compartment 14 for raw vegetables, milk, etc., and for food products left over from one meal to another. However, it is to be understood that any desired arrangement and use of the compartments might be made.

A closed primary refrigerating system associated with cabinet 10 includes an evaporator comprising a conduit 26, coiled back and forth horizontally across and in intimate thermal contact with the top wall of liner 16 of compartment 13, a conduit 28, coiled back and forth horizontally across and in intimate thermal contact with the bottom wall of liner 16 of compartment 13 and a coil connecting conduit 27. The inlet of conduit 26 of the evaporator is connected, by a pipe or conduit 31, to a condenser 32 which is in turn connected by conduit 33 with a motor-compressor unit 34. The outlet of the evaporator or coil 28 is connected, by a

pipe or conduit 36, to the suction side or inlet of the motor-compressor unit 34. Operation of the unit 34 causes evaporated refrigerant in the conduits 26, 27 and 28 of the evaporator to be withdrawn therefrom and circulated into the casing of unit 34. The compressor of unit 34 compresses the refrigerant and forwards same under pressure, through conduit 33, into the condenser 32. The compressed refrigerant may be cooled in any suitable or desirable manner in condenser 32 to liquefy the same therein. Liquid refrigerant is conveyed, by pipe or conduit 31, from condenser 32 in series through conduits 26, 27 and 28 of the evaporator, under the control of any well known or conventional restrictor or expansion valve indicated at 35, for re-evaporation therein to remove heat from the intermediate compartment 13 and for a purpose to be presently described. The motor-compressor unit 34 may be started and stopped in any one of a plurality of well known or conventional manners (not shown). However, it may be desirable to control the operation of unit 34 in response to the temperature of compartment 13 so that the freezing of desserts or water will be given preference in an apparatus of the type disclosed.

Lower food storage compartment 14 is cooled to a temperature considerable above that of compartment 13 by a closed secondary circuit containing a volatile refrigerant and rendered effective by refrigeration produced by the evaporator of the primary refrigerating system. This closed circuit includes a flat tank-like refrigerant condensing portion 41 having a plurality of pipes or refrigerant evaporating portions 42 communicating therewith and extending downwardly therefrom over and in intimate thermal contact with walls of metal liner 17 of compartment 14. The top wall of tank 41 is secured in intimate thermal contact with the conduit coil portion 28 of the primary evaporator. Pipes 42 may extend entirely around the side walls and bottom of liner 17 or they may terminate adjacent a central point along the liner bottom wall. Refrigerant in this circuit vaporizes within the pipes 42, upon absorbing heat from compartment 14, through the walls thereof, and the evaporated refrigerant rises to tank 41 wherein it is cooled by the refrigerating effect produced by coil 28, and liquefied. The liquefied refrigerant then flows downwardly in pipes 42 for re-evaporation therein.

In order to cool the upper cold storage compartment 12 by another closed secondary refrigerating circuit rendered effective by a primary evaporator located therebelow, I employ a closed refrigerating circuit of the type fully disclosed in the patent to Richard S. Gaugler No. 2,350,348 issued June 6, 1944. In the present disclosure the refrigerant condensing portion of this additional closed secondary circuit is in the form of a substantially flat tank 46 having its bottom wall disposed in intimate thermal contact with the coiled conduit evaporator portion 26 of the primary refrigerating system. A plurality of tubes or pipes 47 lead from the tank 46 upwardly along the side walls and partially across the top wall of metal liner 15 of compartment 12. These tubes 47 are constructed in accordance with the disclosure of the Gaugler patent referred to and each includes a sintered or porous metal rod 48 forming a capillary means positioned therein and extending below the end of the tubes into liquid refrigerant within the tank 46. A passage is provided in or along the metal rod between the upper ends of tubes 47 and the tank 46. In the operation

of this secondary circuit the volatile liquid refrigerant therein will climb, due to capillary action, up through the porous capillary structures or rods 48 in the tubes 47 where it will evaporate upon absorbing heat from compartment 12 through walls thereof. This evaporated refrigerant will collect in the upper portion of tubes 47 and by progressive accumulation there, together with its tendency to flow to the coldest portion of the circuit, will be forced down through the passage at the side of the rods 48 and will escape through the liquid refrigerant to the space above the level thereof within tank 46 where it will condense. In this manner heat is transmitted downwardly through evaporation and condensation and liquid refrigerant is raised upwardly without expenditure of any work in raising the liquid to cool the upper compartment 12.

In effecting utilization of the various compartments of the refrigerator disclosed as hereinbefore described, I place the tank or condensing portion 46 of the secondary circuit, employed to cool the upper compartment, in contact with the coil portion 26 of the evaporator conduit which is adjacent the restrictor or expansion valve employed for controlling entrance of refrigerant into the primary evaporator. It is well known that this portion of a series coil type refrigerant expansion evaporator is considerably colder than the coil portion 28 adjacent the outlet of the evaporator. By the arrangement disclosed freezing within compartment 13 may occur at very low temperatures while at the same time permitting functioning of the secondary circuit, associated with the portion or coil 26 of the primary evaporator, to produce a holding temperature of approximately 24° to 28° F. within the pre-frozen food storage compartment 12. The condensing portion of the secondary circuit, employed to cool the lower compartment, being in contact with the coil portion 28 of the evaporator of the primary refrigerating system will permit this circuit to function to produce a somewhat higher temperature within compartment 14 for the preservation of food products required to be stored in temperatures of say for example from 40° to 50° F.

From the foregoing it will be seen that I have provided an improved household refrigerating apparatus wherein compartments thereof are insulated one from another and maintained at different temperatures relative to one another by rendering two secondary refrigerant circuits operative by a novel arrangement or association thereof with an evaporator of a primary refrigerating system. The construction and arrangement of a refrigerating apparatus as herein disclosed meets substantially all of the refrigeration requirements encountered in the ordinary household. The construction is compact and does not materially increase the over-all size of a household refrigerator.

While the form of embodiment of the invention as herein disclosed constitutes a preferred form, it is to be understood that other forms might be adopted, as may come within the scope of the claims which follow.

What is claimed is as follows:

1. A refrigerating apparatus comprising in combination, a cabinet having therein an upper food storage compartment, a lower food storage compartment and an intermediate compartment all insulated from one another, a closed primary refrigerating system associated with said cabinet and including an evaporator for cooling said intermediate compartment, a closed secondary

circuit containing a volatile liquid refrigerant for cooling said lower compartment including a refrigerant condensing portion in heat exchange relationship with the evaporator of said primary refrigerating system and refrigerant evaporating portions extending into heat exchange relationship with said lower compartment, another closed secondary circuit containing a volatile liquid refrigerant for cooling said upper compartment, and said another closed secondary circuit including a refrigerant condensing portion in heat exchange relationship with the evaporator of said primary refrigerating system and refrigerant evaporating portions extending upwardly into heat exchange relationship with said upper compartment.

2. A refrigerating apparatus comprising in combination, a cabinet having therein an upper food storage compartment, a lower food storage compartment and an intermediate compartment all insulated from one another, a closed primary refrigerating system associated with said cabinet and including an evaporator for cooling said intermediate compartment, a closed secondary circuit containing a volatile liquid refrigerant for cooling said lower compartment including a refrigerant condensing portion in heat exchange relationship with the evaporator of said primary refrigerating system and refrigerant evaporating portions extending into heat exchange relationship with said lower compartment, another closed secondary circuit containing a volatile liquid refrigerant for cooling said upper compartment, said another closed secondary circuit including a refrigerant condensing portion in heat exchange relationship with the evaporator of said primary refrigerating system and refrigerant evaporating portions extending upwardly into heat exchange relationship with said upper compartment, said another closed circuit containing capillary means extending from said condensing portion to said evaporating portion thereof and also having connecting passages extending between said portions, and said capillary means being in contact with liquid refrigerant in the condensing portion of said another circuit.

3. A refrigerating apparatus comprising in combination, a cabinet having therein an upper food storage compartment, a lower food storage compartment and an intermediate compartment all insulated from one another, a closed primary refrigerating system associated with said cabinet and including an evaporator for cooling said intermediate compartment, a closed secondary circuit containing a volatile liquid refrigerant including a refrigerant condensing portion in heat exchange relationship with the evaporator of said primary refrigerating system and refrigerant

evaporating portions extending in heat exchange relationship over a plurality of walls of said lower compartment for cooling the interior thereof through said walls, another closed secondary circuit containing a volatile liquid refrigerant for cooling said upper compartment, said another closed secondary circuit including a refrigerant condensing portion in heat exchange relationship with the evaporator of said primary refrigerating system and refrigerant evaporating portions extending upwardly into heat exchange relationship with said upper compartment, said another closed circuit containing capillary means extending from said condensing portion to said evaporating portions thereof and also having connecting passages extending between said portions, and said capillary means being in contact with liquid refrigerant in the condensing portion of said another circuit.

4. A refrigerating apparatus comprising in combination, a cabinet having therein an upper food storage compartment, a lower food storage compartment and an intermediate compartment all insulated from one another, a closed primary refrigerating system associated with said cabinet and including an evaporator for cooling said intermediate compartment, said evaporator comprising a first cooling portion in contact with the upper wall of said intermediate compartment and a second cooling portion in contact with the lower wall of said intermediate compartment, a closed secondary circuit containing a volatile liquid refrigerant for cooling said lower compartment including a refrigerant condensing portion in heat exchange relationship with said second cooling portion of said primary evaporator and refrigerant evaporating portions extending over walls of said lower compartment in contact therewith, another closed secondary circuit containing a volatile liquid refrigerant for cooling said upper compartment, and said another closed secondary circuit including a refrigerant condensing portion in heat exchange relationship with said first cooling portion of said primary evaporator and refrigerant evaporating portions extending over walls of said upper compartment in contact therewith.
